T. STEIN

LIMIT REGULATOR

Filed May 28, 1923

Inventor:
Theodor Stein,
by Alphonse S. Laut.
His Attorney.

UNITED STATES PATENT OFFICE.

THEODOR STEIN, OF SCHONEICHE, GERMANY, ASSIGNOR TO GENERAL ELECTRIC COMPANY, A CORPORATION OF NEW YORK.

LIMIT REGULATOR.

Application filed May 28, 1923. Serial No. 641,984.

To all whom it may concern:

Be it known that I, THEODOR STEIN, a citizen of the Republic of Switzerland, residing at Schoneiche, Germany, have invented certain new and useful Improvements 5 in Limit Regulators, of which the following is a specification.

This invention relates to automatic regulators which are employed to maintain speed 10 values, current values, pressure values and the like between certain predetermined limits.

More particularly this invention relates to automatic pressure regulators for centrifugal compressors which may be adjusted to maintain the pressure values in the discharge conduit of such compressors between 15 any desirable predetermined limits.

The object of this invention is to provide 20 an improved regulator of the above type which is positive and sensitive in operation, which has no lost or ineffective motion in its operating stroke and which is simple in structure and operation.

For a consideration of what I believe to 25 be novel and my invention, attention is directed to the accompanying drawing, description and appended claims.

In the drawing, Fig. 1 is a diagrammatic view partly in section of one embodiment of the invention as applied to a centrifugal compressor installation; Fig. 2 is an enlarged view of the diagrammatic representation of the regulator shown in connection 30 with Fig. 1; Figs. 3, 4, 5 and 6 are sectional diagrammatic views of modifications of the form of the invention shown in Fig. 2.

Referring to Figs. 1 and 2, a centrifugal 40 compressor 7 having an intake conduit 8 and a discharge conduit 9, is shown directly connected with an elastic fluid turbine 10. The turbine is supplied with operating fluid through a conduit 11 and a throttle valve 12. The throttle valve 12 is controlled in 45 the usual way by means of a hydraulic gear 13 having its floating control lever 14 mounted below it, the arrangement being such that a downward movement of a free end 15 of the lever 14 will cause the throttle valve 12 to close a corresponding amount while an upward movement of the end 15 will cause the throttle valve 12 to open a corresponding amount. As this device is well known in connection with elastic fluid

turbines further description is believed to be unnecessary.

In this particular installation with which it will be understood the invention is shown only by way of example, it is assumed that 60 the pressure in the discharge conduit 9 of the compressor 7 is to be kept within certain allowable limits, for example, between five atmospheres maximum and one atmosphere minimum, by varying the speed of the 65 turbine and hence the speed of the compressor and the pressure delivered by it to the discharge conduit 9. To do this automatically, a regulator embodying the invention is inserted, as a connecting and controlling link, between the pressure in the compressor discharge conduit 9 and the free end 15 of the hydraulic gear control lever 14, being mounted adjacent the latter in a hollow pedestal casing as shown at 16. 70

A cylinder 17 formed at the upper end of the casing 16 carries a movable abutment 18 and an actuating spring 19 compressed between the latter and the upper end of said cylinder. The actuating spring 80 19 tends to move the abutment 18 downwardly against a pressure supplied beneath it through a pressure line 20 connected at one end with the discharge conduit 9 of the compressor, and at the other end with the 85 cylinder at a point sufficiently near the lower end of the latter to insure pressure beneath the movable abutment throughout its entire travel.

The surface area of the movable abutment 90 18 and the strength of the actuating spring 19 are so proportioned relatively to each other that the movable abutment will assume a normal balanced position as shown, substantially midway between the ends of 95 the cylinder when the pressure below it reaches the upper allowable limit of five atmospheres, this pressure being just sufficient to balance the downward thrust of the actuating spring 19 with the movable 100 abutment in this position.

Any increase or decrease in pressure will cause an unbalancing and a tendency on the part of the abutment to move to a new position of equilibrium, which movement is 105 used to actuate the floating control lever 14 of the hydraulic gear 13 to correct such increase or decrease by a corresponding change in speed of the turbine. For this purpose, the abutment 18 is provided with a rod 21 110

extending axially downwardly from it through the center of the pedestal casing and pivotally connected at a point 22 between its ends with one end of a horizontal lever 23. This lever passes outwardly through an opening 24 in the casing to a point substantially vertically below the end 15 of the floating control lever 14 and is connected therewith by a link 25 having a pivot at either end. The lever 23 is pivotally mounted on a horizontal stud 26 carried by an ear 27 extending outwardly from the casing adjacent the opening 24. This opening is of sufficient vertical length to permit a full operating swing of the lever 23.

The above described lever arrangement is such that an upward movement of the abutment 18 will cause a corresponding downward movement of the end 15 of the floating control lever 14, a corresponding closing of the throttle valve 12 and, through the accompanying reduction of speed, a corresponding reduction in pressure in the discharge conduit 9 of the compressor while conversely a downward movement of the abutment 18 will cause a corresponding increase in pressure in said compressor discharge conduit.

Because of fluctuations in the pressure of the motive fluid delivered to the turbine, the speed and consequently the discharge pressure of the compressor will vary, and also for any given speed the pressure in the discharge conduit will vary because the demand will usually increase and decrease between wide extremes, hence to meet these conditions ordinarily requires a regulator with an actuating member which travels a considerable distance between effective operating and controlling portions of its stroke, rendering such a regulator less sensitive than is desirable and of large dimensions or else requires the use of two regulators, one for each pressure limit, resulting in a complicated regulating means.

As a result of the present invention, however, one regulator serves to control both limits and without any actuating control part thereof moving between the limits, resulting in greater sensitivity and less complicated parts. This is accomplished according to the invention through the use of an auxiliary spring 28 seated in the bottom of the casing and compressed beneath a stop disk 29 to such a degree that it biases said stop disk upwardly against an annular stop shoulder 30, formed in the casing walls, with a force equal to the difference between that exerted against the actuating spring 19 by the movable abutment 18 when under the influence of the maximum allowable pressure of five atmospheres and that when the same is under the influence of the minimum allowable pressure of one atmosphere. By

means of rod 21, provided with a foot 31 at its lower end arranged to make contact with the disk 29 as soon as the pressure below the movable abutment 18 fails to balance the actuating spring above it, the auxiliary 70 spring 28 receives through said rod 21 and the stop disk 29 the downward thrust on the movable abutment resulting from such decrease in pressure below it and prevents it from moving until this pressure falls to the 75 lower limit of one atmosphere. With any further decrease in pressure below the abutment 18, the auxiliary spring 28 is unable to supply the deficiency and begins to yield, allowing the abutment 18 to move downwardly and operate the throttle valve through the lever linkage as hereinbefore described. This will bring about an increase in the speed of the turbine until the pressure again comes within the predetermined limits when 85 the movable abutment returns to its normal position.

It will thus be seen that the auxiliary spring 28 is set to function passively as a holding means to prevent the movable abutment 18 from moving downwardly from the normal position while the pressure in the discharge conduit 9 remains above the lower predetermined limit of one atmosphere. The actuating spring 19 prevents the movable abutment from moving upwardly from said normal position while the pressure in the discharge conduit 9 remains below the predetermined upper limit of five atmospheres, being set as hereinbefore described, 90 to exactly balance the movable abutment in the normal position shown when the upper pressure limit is reached, hence the throttle valve and the operation of the turbine is not subjected to continual operation or any 105 "hunting" action while the pressure in the discharge conduit of the turbine remains between these limits. If the pressure in the conduit 9 does exceed the upper limit of five atmospheres, the abutment will be 110 moved upwardly by such pressure which will over-balance the actuating spring pressure. The foot 31 of rod 21 will leave the stop disk 29 as the abutment moves upwardly leaving the auxiliary spring 28 out 115 of the action above this point. This upward movement of the movable abutment will cause a decrease in the pressure delivered by the compressor as described hereinbefore.

As to the setting of the regulator for any given compressor installation the pressure limits are decided upon and the upper or actuating spring 19 is chosen in relation to the surface area of the movable abutment 18 as hereinbefore mentioned to receive and hold said movable abutment in substantially the mid position shown, which is the normal position, when the upper limit of pressure is reached, by moving the end 15 of the floating control lever 14 to the proper position 120

to obtain the speed required to produce this pressure, the distance between the outer end of the lever 23 and said end 15 then determines the length of the link 25 to be inserted 5 between them. This position of the movable abutment also determines the length of the rod 21 extending downwardly from it, as the foot 31 at its lower end should be just on the point of making contact with the stop disk 29 at this time. The auxiliary spring is designed to hold the disk 29 against the stop shoulder 30 with a force sufficient to hold the movable abutment from moving until the pressure reaches the lower limit. Thus it is 10 seen that the spring 28 must be weaker than spring 19 and be able to resist the downward thrust of the latter only when assisted by a pressure, supplied from the discharge conduit 9 beneath the abutment 18, of a value 15 in excess of the lower allowable pressure limit.

The regulator shown in Figs. 1 and 2 may be adapted without any material change to control a valve directly, as will be noted 20 now in referring to Fig. 3, in which the same reference numerals have been used as for like parts in the preceding figures, except that the exponent "b" is added.

In this figure the regulator is shown 25 mounted directly on a conduit 32 and connected with a valve 33 within said conduit, which controls an opening 34 between a region of higher pressure 35 and a region of lower pressure 36, the flow being in the 30 direction of the arrow when the valve is open. The region of higher pressure 35 might, for example, be connected with the discharge conduit of a compressor while the region of lower pressure 36 might lead to 35 the atmosphere. In this case the valve 33 would serve as a relief valve to maintain the pressure in the discharge conduit of said compressor between certain pressure limits.

The space below the movable abutment 40 45 18^b is connected with the region of higher pressure 35 through a pressure line 20^b while the valve 33 is connected with the movable abutment through an extension of the rod 21^b indicated at 37. This extension 50 is connected with the foot 31^b of rod 21^b and passes through an opening 38 in stop disk 29^b and axially downwardly through the casing at 39 to the valve 33. The length 55 of this extension is such that in this particular installation the valve is maintained in the partly open position when the movable abutment 18^b is in the normal position both substantially as shown. This is because it is assumed that the relief valve 33 60 must be partially open normally to provide constant control.

The operation of the regulator is the same as in the previous figures, that is, when a predetermined maximum pressure is 65 exceeded in the region of higher pressure

35 the movable abutment overcomes the downward pressure of the actuating spring 19^b and opens the valve 33 more fully to relieve the pressure. When the pressure in the region of higher pressure 35 passes below a predetermined lower limit the auxiliary spring 28^b and the pressure then existing below the abutment 18^b are no longer sufficient to resist the action of the actuating spring 19^b and the valve is moved toward 70 the closed position until the pressure value 75 in the higher pressure region 35 is corrected.

In the form of the regulator embodying the invention shown in Fig. 4 in which 80 reference numerals used for similar parts in the preceding figure have been used with the exponent "c" added, again it will be noted that no general departure from the construction of the preceding figures is 85 made.

This is a regulator which is operated by changes in the flow of current through an electrical circuit indicated at 40 instead of through changes of pressure in a fluid conduit. For this purpose a solenoid 41 is inserted in the circuit 40 and adapted to move the abutment 18^c. The abutment 18^c is connected with a magnetic core 42 within the solenoid and is biased upwardly with increasing force as the current flowing through the solenoid increases to a predetermined upper limit, beyond which the opposing force of the actuating spring 19^c is overcome and the movable abutment is carried upward 95 a corresponding amount. A guide rod 43 connected with the movable abutment and passing upwardly through an opening 44 in the top of the casing 16^c serves as a means for connecting the movable abutment with 100 any suitable controlling device, for example, a device to control the current flowing in the solenoid, in which case the arrangement is such that an upward movement of the solenoid core 42 and movable abutment 105 18^c will cause a decrease in the current flow and a downward movement an increase.

The movable abutment is prevented from downward movement under the action of the actuating spring 19^c by the foot 31^c of 110 the rod 21^c bearing against the stop disk 29^c which in turn is held from downward movement by an auxiliary spring 28^c compressed beneath it sufficiently to allow no movement 115 of said stop disk 29^c until the current flow in circuit 40 and hence the upward pull of the solenoid on the core 42 falls to a certain lower predetermined limit, when on further decrease in the current flow, spring 28^c 120 yields and permits the abutment 18^c to move 125 downwardly actuating the current controlling device as pointed out above.

In Fig. 5 a departure from the form of the regulator employed in the preceding figures is shown by way of example to illus- 130

trate the adaptability of the invention to various needs. A rearrangement of the component parts of the regulator of Fig. 2 is provided, these parts bearing the same number as like parts in Fig. 2 with the exponent "d" added.

In this embodiment of the invention a casing 16^d is divided into an upper chamber 45 containing an auxiliary spring 28^d and a lower chamber 46 containing an actuating spring 19^d. A wall 47 between the chambers serves as a seat for both springs.

The actuating spring 19^d is compressed between the wall 47 and a movable abutment 18^d provided at one end of a horizontal lever 48, to bias the abutment downwardly against a block 49 which in turn rests on a flexible diaphragm 50. The diaphragm covers an opening 51 in a casing 52 in which exists a pressure the value of which is used to determine the position of a relief valve 53. This valve is positioned over a relief opening 54 through which a fluid flows in the direction of the arrows, and is carried normally partially open on the opposite end of the lever 48 from that of abutment 18^d. The lever is pivoted between its ends as indicated at 55 and passes into the casing through an opening 56. The arrangement is such that an increase in pressure below the diaphragm 50 will tend to bow it upwardly to move the abutment 18^d against the biasing action of spring 19^d. This in turn will cause a closing action of the valve 53 over the relief opening 54.

The actuating spring 19^d is designed to hold the movable abutment 18^d against any force exerted on the diaphragm 50 until a certain predetermined upper pressure limit is reached; above which it yields proportionately to the excess pressure and permits the valve 53 to move toward the closed position over the opening 54.

Upon a decrease in pressure below the diaphragm 50, the movable abutment is prevented from moving downwardly to more fully open the valve 53, by a rod 21^d which extends from it axially upward through the casing to a point just above a stop disk 29^d, openings 57 and 58 being provided for it in wall 47 and stop disk 29^d respectively. At this point just above stop disk 29^d a head 31^d is formed on the rod and positioned relative to the disk 29^d so that it will make contact with said disk upon the least downward movement of the abutment 18^d from its normal position shown. It will be understood that the normal position is determined by increasing the pressure below the diaphragm 50 to the upper predetermined limit, at which time the abutment will be balanced between the pressure of the diaphragm 50 below and that of the actuating spring 19^d above. The valve 53 is then positioned on the end of lever 47 to the desired distance from the re-

lief opening 54 and the head 31^d is then made to be just on the point of making contact with the stop disk 29^d.

As in the preceding figures, the stop disk 29^d is biased by the auxiliary spring 28^d 70 against a stop shoulder 30^d provided at the top of the casing, with a force which is sufficient to hold the abutment 18^d from downward movement until the pressure beneath it (in this case that existing beneath the diaphragm 50) falls to a certain predetermined value when spring 28^d yields and permits the actuating spring 19^d to move the abutment downwardly and open the relief valve 53. 75

Thus the relief opening 54 is controlled 80 by the pressure in the casing 52, being more fully closed in proportion as the pressure in casing 52 exceeds a certain predetermined higher value and being more fully opened as the pressure in casing 52 falls below a 85 predetermined value, but is held to a certain fixed normal opening while the pressure in casing 52 remains between said predetermined higher and lower limits. This control is accomplished through one regulator 90 embodying few and simple parts, and like the previously described embodiments of the invention represents but one of many regulator applications to which the invention 95 may be adapted.

To illustrate the extent to which the invention may be adapted to various control devices to provide them with the limit feature which the invention embodies, in Fig. 6 a revolving fly weight governor is shown 100 embodying the invention. As in the preceding figures, parts of this figure have the same reference numerals with the exponent "e" added as similar parts appearing throughout the drawing.

This is a common type of engine governor having two fly weights 59, 59 revolving on the ends of two upper arms 60, 60 pivotally connected at their upper ends at 61 with a central driving shaft 62. 105

The weights 59, 59 are acted upon by centrifugal force, represented by the arrows, as they revolve and tend to move apart against the action of a retracting spring 19^e connected between them and so 110 tensioned that it will not permit them to move from the position shown, which is the normal position, until a certain upper speed limit is reached. With the speed below this upper limit this spring tends to overcome the centrifugal force acting on the fly weights and move them together, but this is prevented until a certain lower limit of speed is reached, through a movable abutment 18^e in the form of a sliding sleeve 115 connected with each weight by a link 63 bearing downwardly on a stop disk 29^e. This stop disk is in turn held from downward movement by an auxiliary spring 28^e seated in the bottom of a hollow casing 16^e. 120 125 130

This casing may be part of the mechanism with which the governor is associated or a separate housing. It serves to support the shaft 62 which passes axially upwardly

5 through it and is formed at its upper end with a stop shoulder 30° for the disk 29°.

The auxiliary spring 28° presses the stop disk upwardly against the stop shoulder 30° with a force sufficient to hold the downward 10 thrust of the movable abutment 18° as the speed decreases to a predetermined lower limit when it yields to the superior force of the spring 19° and permits the movable abutment 18° to move downwardly.

15 A lever 23° pivotally mounted at a point between its ends on an ear 27° extending from the casing 16° and operatively connected at one end with the movable abutment as indicated at 22° serves to transmit

20 the action of the governor to any suitable speed controlling device which may be connected at the other end.

The operation of the governor is similar to that of the regulator of Figs. 1 and 2 in 25 that it operates only when normal operation is departed from to a certain predetermined degree in either direction. That is, the fly weights 59, 59 revolve in the same position relative to each other regardless of speed 30 changes between a certain higher limit and a certain lower limit of speed, but when the higher limit is reached the tension of the spring 19° is just balanced by the centrifugal force then acting on the weights 59, 35 59, the movable abutment is on the point of leaving contact with the stop disk 29° and any further increase in speed will cause the fly weights to move carrying said abutment 18° with them. This in turn moves the lever 40 23° to effect the proper change in the control device, for example, to reduce the speed.

As the speed falls below the upper limit, the balance between spring 19° and the 45 centrifugal force acting on the fly weights is destroyed with the result that the movable abutment is forced against the stop disk 29° by the spring 19° with increasing force until the lower limit of speed is reached. The auxiliary spring plus the 50 centrifugal force then exerted on the fly weights 59, 59 just balance the force of the spring 19°. The stop disk is just on the point of leaving the stop shoulder 30°. Any further decrease in speed will cause the 55 auxiliary spring to yield and permit the movable abutment 18° to be moved downwardly, resulting in the operation for example, of a speed controlling device through the lever 23° to correct this tendency to fall 60 below the lower limit.

It will be understood that this is but one application of the invention to speed controlling devices, and that the invention is not confined to any particular applications 65 herein described and illustrated, but may be

carried out by other means to meet any particular need for a limit regulator.

What I claim as new and desire to secure by Letters Patent of the United States, is:—

1. In a limit regulator, the combination 70 of a movable abutment having a certain range of travel, means providing a variable and a constantly acting force to move the abutment in one direction operatively connected with said abutment, stop means limiting the action of the constantly acting force to less than the full travel of the movable abutment, means providing a second constantly acting force to move the abutment in the opposite direction, and control 75 means operatively connected with said movable abutment to be actuated by movement thereof.

2. A regulator operated by and controlling a varying force through a movable member embodied in its structure, said regulator being characterized by the fact that its movable member is held stationary between certain predetermined higher and lower limits in the magnitude of the varying force. 85

3. The combination with a governing mechanism, of a regulator comprising a movable member connected with and controlling said mechanism, means providing a varying force controlled by the governing mechanism to act on the member to move it, means preventing movement of the member in one direction when the magnitude of said force is of a value below a certain predetermined higher limit, and an auxiliary means preventing movement of the member in the opposite direction when the magnitude of said force is of a value above a certain predetermined lower limit. 95

4. A regulator comprising a movable member, means providing a constantly acting force and a variable force to act thereon in opposition, the variable force being normally less than the first named force whereby 110 the member is normally biased in the direction of said variable force, means providing an auxiliary force to act supplementary to the variable force to balance the member against the constantly acting force as the variable force assumes any value between a certain higher predetermined limit at which the latter force alone equals the first-named force and a certain lower predetermined limit at which the variable force and the auxiliary force combined equal the first-named force whereby the member is held stationary between said limits, means preventing the supplementary action of the auxiliary force when the variable force assumes 115 a value at and above the predetermined higher limit whereby the member is moved by the variable force as it exceeds said limit and becomes greater than the constantly acting force, said auxiliary force being set to 120

yield to the constantly acting force as the variable force falls below the predetermined lower limit whereby the member is moved by the constantly acting force, and control means operatively connected with the movable member to be actuated by its movement.

5. In combination, a movable member, means biasing said member in a certain positive direction, means providing a variable force to bias the movable member in an opposite negative direction, said first-named means being set to yield to the opposing variable force when the latter passes above a predetermined higher limit whereby the 10 member is moved in said negative direction, said first-named means being normally superior to the variable force, whereby the member is normally biased in the first-named positive direction, auxiliary means provided 15 to act upon the movable member in conjunction with and supplementary to the variable force, said auxiliary means so acting only when the variable force falls below the higher predetermined limit to hold the movable 20 member stationary from moving in the positive direction, said auxiliary means being set to yield when a certain predetermined lower limit is reached by the variable force and to permit the member to be moved 25 in the positive direction through action of the first-named means, and means preventing the supplementary action of the auxiliary means when the variable force assumes a value at and above the predetermined higher 30 limit.

6. In combination, a movable member, means biasing said member in a certain positive direction, means providing a variable force to bias the movable member in an opposite negative direction, said first-named means being set to yield to the opposing variable force when the latter passes above a predetermined higher limit whereby the member is moved in said negative direction, 40 said first-named means being normally superior to the variable force, whereby the member is normally biased in the first-named positive direction, auxiliary means provided to act upon the movable member in conjunction with and supplementary to the variable force, said auxiliary means so acting only when the variable force falls below the higher predetermined limit to hold the movable member stationary from moving in the positive direction, said auxiliary means being set to yield when a certain predetermined lower limit is reached by the variable force and to permit the member to be moved in the positive direction through action of the first-named means, a device for controlling the value of the variable force, and means connecting the movable member with said controlling device such that a movement of the member in the positive direction will cause 45 a corresponding increase in the variable

force while a movement of the member in the negative direction will cause a corresponding decrease in the variable force.

7. The combination with a centrifugal compressor or the like having a discharge conduit to which it supplies a pressure at a value determined by its speed, of a regulator controlling its speed, comprising a movable member upon the position of which the speed of the compressor depends, means biasing said member to a position to increase the speed, means supplying pressure from the discharge conduit of the compressor to bias the member to a position to decrease the speed, said first-named means preventing movement of the member by the pressure supplied by said second-named means until the latter exceeds a certain predetermined higher limit, and an auxiliary means preventing movement of the member by said first-named means until the pressure supplied by said second-named means falls below a certain predetermined lower limit.

8. The combination with a centrifugal compressor or the like and a device for controlling its speed, of a pressure regulator comprising a movable member operatively connected with the speed controlling device, means supplying pressure delivered by the compressor to act upon the member to move it, means preventing movement of the member below a certain predetermined higher limit of said pressure and an auxiliary means preventing movement of the member above a certain predetermined lower limit of 100 said pressure whereby said member is held stationary and the speed controlling device inoperative while the pressure supplied by the compressor remains between said limits.

9. The combination with a centrifugal compressor or the like having a discharge conduit and an associated mechanism for controlling its speed, of a pressure regulator forming an operative connection between said mechanism and the pressure supplied by the compressor to said discharge conduit and comprising a movable member connected with said mechanism to operate the same by its movement, means supplying pressure from the compressor discharge conduit 105 to the movable member to bias said member in a direction to lower the speed through the controlling mechanism, means supplying a normally superior force biasing said member in the opposite direction to raise the speed through the controlling mechanism, said last-named means being set to yield to the biasing action of pressure supplied from the compressor discharge conduit when said pressure passes above a certain predetermined higher limit whereby the member is moved and the speed reduced, an auxiliary means providing a supplementary force to act on the movable member in conjunction with the pressure supplied from the 110

compressor discharge conduit when the latter falls normally below the predetermined higher limit to hold the movable member against the biasing action of the first-named means, said last-named auxiliary means being set to yield to the force of the first-named means when the pressure supplied from the conduit falls below a certain predetermined lower limit and permit the member to be moved in a direction to raise the speed through the controlling mechanism.

10. In a limit regulator, the combination with a movable abutment, of means providing a variable force, the magnitude of which is to be regulated, to act thereon to move it, means providing a biasing force continually acting upon the abutment to move it in opposition to said first-named force whereby said abutment tends to be moved to positions wherein a balance is effected between said opposing forces, the value of the biasing force being such that the abutment is in a balanced normal position when the variable force assumes a certain predetermined high value, a yieldable stop means for the abutment which receives the thrust of the biasing force when the variable force falls below said predetermined high value, said stop means being set to yield and permit the abutment to move when the variable force falls below a certain predetermined low value, and control means for said variable force operatively connected with the

abutment to be actuated by movement thereof.

11. In a limit regulator, the combination with a movable abutment, of means providing a variable force, the magnitude of which is to be regulated, to act thereon to move it, a spring connected with said abutment to move it in opposition to said variable force, whereby said abutment tends to be moved to positions wherein a balance is effected between the variable force and that set up by the spring, said spring being adjusted to provide a force equal to a certain predetermined high value of the variable force when the abutment is in a certain normal position, a second spring providing a stop means for the abutment to hold the same immovable when the variable force falls below the predetermined high value and being set to yield and permit the abutment to move when said variable force falls below a certain predetermined low value, said last-named spring being operatively disconnected from the abutment when the variable force reaches and exceeds said predetermined high value, and control means for the variable force operatively connected with the abutment to be actuated by movement thereof.
